UNITED STATES PATENT OFFICE

166,370

LIGHTING FIXTURE

Paul D. Wilson, Greensburg, Pa., assignor to
Imperial Lighting Products Company, Inc.,
Greensburg, Pa., a corporation of Pennsylvania

Application November 17, 1950, Serial No. 13,036

Term of patent 14 years

(Cl. D48—4)

To all whom it may concern:

Be it known that I, Paul D. Wilson, a citizen of the United States, residing at Greensburg, county of Westmoreland, State of Pennsylvania, have invented a new, original, and ornamental Design for a Lighting Fixture, of which the following is a specification, reference being had to the accompanying drawing, forming a part hereof.

Fig. 1 is a front perspective view of a lighting fixture, showing my new design;

Fig. 2 is a side elevational view taken from the right of Fig. 1; and

Fig. 3 is a top plan view thereof.

I claim:

The ornamental design for a lighting fixture, as shown.

PAUL D. WILSON.
